(57) **CLAIM**

The ornamental design for a lanyard clasp, as shown and described.

DESCRIPTION

FIG. 1 is a front, left and top perspective view of a lanyard clasp, showing my design.

FIG. 2 is a front, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another perspective view of the lanyard clasp in a usable state.

The broken line depicts that the environmental part of the lanyard clasp does not constitute the protective part of the required design.
